LIQUID DETERGENT COMPOSITIONS

Daniel A. Cook, Mentor Township, Lake County, Ohio, assignor to Diamond Alkali Company, Cleveland, Ohio, a corporation of Delaware

No Drawing. Filed Oct. 15, 1956, Ser. No. 615,761

3 Claims. (Cl. 252—153)

This invention relates to a novel liquid detergent composition, and more particularly relates to a new and improved liquid detergent characterized by excellent cleansing power and larity throughout a wide range of temperatures and with water of varying degrees of hardness.

Until fairly recently, general purpose detergents frequently have been solid powders comprising mixtures of alkali and soap adapted to be dissolved in water and applied as solutions. Various liquid organic substances, notably liquid non-ionic wettable agents, have demonstrated superiority in soil removal, sudsing ability and other desirable properties and have been proposed as additives to powdered detergents. These liquids are, of course, limited in the amount in which they can be incorporated into a powder or granular material without destroying its particulate nature. Moreover, dusting and caking of dry detergents are frequently difficult to control so that considerable interest has been directed toward liquid detergents.

Liquid detergents have found application in a variety of washing and cleansing operations, e.g., in dishwashing, windowwashing, hand cleaning, machinery cleansing and a variety of applications in the dairy industry in cleaning milking machines, inflations, utensils, milk tanks, pipe lines, milk cans, and the like.

Prior liquid detergents comprising a major portion of liquid non-ionic additives, or a mixture of non-ionic and anionic surface active agents have not been completely satisfactory. Anionic materials alone frequently do not provide desirable results in hard water. On the other hand, it has been found that a liquid non-ionic substance by itself does not provide an entirely satisfactory material, notably because of a disadvantageous cloud point. Accordingly, there has been a continuing interest in seeking new and improved liquid detergents.

Accordingly, it is a principal object of the present invention to provide a new and improved general purpose liquid detergent which avoids the difficulties heretofore encountered.

A further object of this invention is to provide a new and improved liquid detergent which is characterized by a desirable viscosity, color, film characteristics, hard water resistance, cold weather properties and excellent detergency.

These and other objects and advantages of the present invention will appear more fully from the following description thereof.

The present invention contemplates a liquid detergent composition comprising in admixture the following ingredients:

	Parts
(a) Alkyl aryl sulfonate (100% active).....	6-9
(b) Alkyl aryl polyether alcohol (100% active).....	23-26
(c) At least one substance selected from the group consisting of:	

2

	Parts
(1) Alkanolamides (100% active).....	2-5
(2) Polyoxyalkylene alkanols (100% active).....	3-6
(d) Antifreeze.....	0-10
(e) Sequestrant.....	0-5
(f) Water.....	10-35

A liquid detergent composition of the above type is found to have a desirable viscosity and yet is not thick enough to cause difficulty in pouring nor is it subject to freezing at any typically-encountered low temperature. Further, a liquid detergent of the above composition has a desirable color, excellent sudsing characteristics, and is characterized by clarity and an absence of cloud point up to 100° C. and an excellent hard water resistance whereby clear solutions are provided in water having hardness values ranging from 10-100 grains or more.

The expression "alkyl aryl sulfonate" as used throughout the specification and claims is intended, of course, to refer to various alkyl aryl sulfonates and their alkali metal salts such as sodium salts, potassium salts, and the like. Preferred alkyl aryl sulfonates are alkyl benzene, toluene, and/or naphthalene sulfonates where the alkyl group contains from about 4 to 18, preferably 10-14, carbon atoms, e.g., sodium dodecyl aryl derivatives derived from propylene tetramer or kerosene fractions (keryl) averaging 12 carbon atoms. A specific preferred alkyl aryl sulfonate is sodium dodecyl benzene sulfonate. Such a material is available commercially as Ultra-Wet 35 KX which typically comprises an aqueous solution of 68% by weight water and 32% by weight sodium dodecyl benzene sulfonate.

The expression "alkyl aryl polyether alcohol" as used throughout the specification and claims is intended, of course, to refer to various alkyl aryl polyether alkanols, notably ethanol, such as alkyl benzene polyoxyethylene hydroxides. These compounds can be prepared by constituent isocyclic hydroxy compounds having as a substituent in the nucleus at least one hydrocarbon or acyclic radical of at least 4 carbon atoms, with ethylene oxide. Suitable isocyclic compounds are normal butyl phenol, diisobutyl phenol, dodecyl phenol, and the like. The condensation can be carried out at an elevated temperature in the presence of an alkali. For example, 206 parts by weight of p-isooctyl phenol are melted and combined with 2 parts by weight of a 40% caustic soda solution. To this mixture there is introduced ethylene oxide at 120°-130° C. until a total of 10 molecules have been adsorbed for each molecule of the phenol. 50 A commercially available product of this type is Triton X-100.

The term "alkanolamide" as used throughout the specification and claims is intended to refer to various alkanolamides, especially mono- and dialkanolamides such as mono- and diethanolamides, dimethanolamides, ethanolamides, methanolamides, and the like, although a diethanolamide is preferred at present, such as the commercially available product as "Solar CO" which is obtained by reacting coconut oil with diethanolamine and typically comprises a mixture of 72% by weight diethanolamide, 1% by weight diethanolamine laurate, 21% by weight diethanolamine and 6% by weight glycerine.

The expression "polyoxyalkylene alkanol," as used throughout the specification and claims, is intended to refer to various compounds of this type, especially polyoxyalkylene ethanol. An illustrative and preferred polyoxyalkylene ethanol compound is tridecyl polyoxyethylene ethanol. A commercially available material of this type is the product known as Emulphor BC-840 which is a liquid, 100% active polyoxyalkylene ethanol.

The term "antifreeze" as used throughout the specifi-

cation and claims generally refers to organic compounds which may be added to prevent freezing of the liquid detergent composition. At present, it is preferred to employ a mixture of antifreeze compounds, notably a mixture of about equal proportions of (1) an alkylene glycol such as hexylene glycol and (2) an alkanol such as methanol, ethanol, or the like. It will be appreciated, of course, that in certain instances, antifreeze compounds need not be added when the intended application does not involve exposure to freezing temperatures.

The term "sequestrant," as used throughout the specification and claims, is intended to refer to additives capable of preventing sludge formation in hard water or other undesirable clouding. A preferred type of sequestrant at present is the commercially available material known as Sequestrene or Nullapon, which is tetrasodium salt of ethylene diamine tetra-acetic acid. Other polyamino polycarboxylic acids, salts and derivatives thereof, as well as different compatible sequestrants, also may be used.

Liquid detergents embodying the present invention can be prepared by mixing the specified ingredients in the indicated amounts. The proportion ranges specified are critical and should be mentioned if the advantageous results characterizing the practice of this invention are to be obtained.

In order that those skilled in the art may more completely understand the present invention and the preferred methods by which the same may be carried into effect, the following specific examples are offered:

Example I

An illustrative liquid detergent in accordance with the present invention is as follows:

	Percent by weight
Alkyl aryl sulfonate (32% active)	
Ultrawet 35 KX	25.0 (8.0% active)
Alkyl aryl polyether alcohol (100% active) Triton X-100	24.0
Polyoxalkalene alkanol (100% active) Emulphor BC-840	5.0
Hexylene glycol	3.0
Ethanol (denatured)	3.0
Sequestrant (Sequestrene)	0.1
Water	Balance

The above composition has viscosities at 80°, 60° and 40° F., respectively, of 96, 272 and 720 centipoises. Moreover, this product is perfectly clear in 100 grain water at normal use concentrations, i.e., 0.1 to 0.5% by weight liquid detergent of water, typically about 0.25%, from room temperature to the boiling point of solution. In addition, excellent sudsing and suds stability is observed, as well as a high degree of detergency.

Example II

Another illustrative liquid detergent formulation in accordance with the present invention is the following:

	Percent by weight
Alkyl aryl sulfonate (32% active)	
Ultrawet 35 KX	21.7 (7.0% active)
Alkyl aryl polyether alcohol (100% active) Triton X-100	25.0
Alkanolamide (72% diethanolamide)-Solar CO	5.0
Hexylene glycol	3.0
Ethanol (denatured)	3.0
Sequestrant (Sequestrene)	0.1
Water	Balance

It is to be understood that although the invention has been described with specific reference to particular embodiments thereof, it is not to be so limited, since changes and alterations therein may be made which are within

the full intended scope of this invention as defined by the appended claims.

What is claimed is:

1. A liquid detergent composition characterized by a high degree of clarity and absence of a cloud point up to 100° C. and capable of providing clear solutions in water having hardness values ranging from 10 to 100 grains, said detergent comprising in admixture the following ingredients:

	Percent by weight
(a) Sodium dodecyl benzene sulfonate	7-8
(b) Alkyl benzene polyether ethanol	24-25
(c) At least one substance selected from the group consisting of:	
(1) Diethanolamide mixture consisting essentially of 72% by weight diethanolamide, 1% by weight diethanolamine laurate, 21% by weight diethanolamine, and 6% by weight glycerine	5
(2) Tridecyl polyoxyethylene alcohol	5
(d) Hexylene glycol	3
(e) Ethyl alcohol	3
(f) Tetrasodium salt of ethylene diamine tetra-acetic acid	0.1
(g) Water	Balance

2. A liquid detergent composition characterized by a high degree of clarity and absence of a cloud point up to 100° C. and capable of providing clear solutions in water having hardness values ranging from 10 to 100 grains, said detergent comprising in admixture the following ingredients:

	Percent by weight
(a) Sodium dodecyl benzene sulfonate	7
(b) Alkyl benzene polyether ethanol	25
(c) Diethanolamide mixture consisting essentially of 72% by weight diethanolamide, 1% by weight diethanolamine laurate, 21% by weight diethanolamine, and 6% by weight glycerine	5
(d) Hexylene glycol	3
(e) Ethanol	3
(f) Tetrasodium salt of ethylene diamine tetra-acetic acid	0.1
(g) Water	Balance

3. A liquid detergent composition characterized by a high degree of clarity and absence of a cloud point up to 100° C. and capable of providing clear solutions in water having hardness values ranging from 10 to 100 grains, said detergent comprising in admixture the following ingredients:

	Percent by weight
(a) Sodium dodecyl benzene sulfonate	8
(b) Alkyl benzene polyether ethanol	24
(c) Tridecylpolyoxyethylene alcohol	5
(d) Hexylene glycol	3
(e) Ethyl alcohol	3
(f) Tetrasodium salt of ethylene diamine tetra-acetic acid	0.1
(g) Water	Balance

UNITED STATES PATENT OFFICE
CERTIFICATE OF CORRECTION

Patent No. 2,943,058

June 28, 1960

Daniel A. Cook

It is hereby certified that error appears in the printed specification of the above numbered patent requiring correction and that the said Letters Patent should read as corrected below.

Column 1, line 18, for "larity" read -- clarity --; line 25, for "wettable" read -- wetting --; column 2, lines 36 and 37, for "constituent" read -- condensing --; line 58, after "product" insert -- known --; same column 2, line 66, for "poly-" read -- polyoxy- --; column 4, line 14, at the end of the line, under "Percent by weight", insert -- 5 --; same column 4, lines 20 and 21, at the end of the line, under "Percent by weight", strike out the numerals "5", each occurrence.

Signed and sealed this 3rd day of January 1961.
